UNITED STATES PATENT OFFICE.

WILLIAM LAFLER, OF LAKE GEORGE, MICHIGAN.

RAILROAD-TIE PLATE.

1,267,234.

Specification of Letters Patent.

Patented May 21, 1918.

Application filed February 9, 1918. Serial No. 216,341.

To all whom it may concern:

Be it known that I, WILLIAM LAFLER, a citizen of the United States, residing at Lake George, in the county of Clare and 5 State of Michigan, have invented new and useful Improvements in Railroad-Tie Plates, of which the following is a specification.

This invention has reference to railway 10 constructions.

An object of the invention is the provision of a tie plate of novel construction between and arranged upon the ties to provide a proper gage for the rails and when engaging 15 with the rails to hold the said rails against creeping, sinking or lateral movement.

Other objects and advantages will appear as the nature of the invention is better 20 understood, reference being had to the accompanying drawings, in which:

Figure 1 is a plan view illustrating the application of the improvement.

Fig. 2 is a sectional view approximately 25 on the line 2—2 of Fig. 1.

Fig. 3 is a sectional view approximately on the line 3—3 of Fig. 2, the rail being removed.

Fig. 4 is a plan view of the body member 30 or plate proper.

Fig. 5 is a perspective view of the same.

Fig. 6 is a view looking toward the outer edge of the slidible clamp.

Fig. 7 is a perspective view of the same.

Fig. 8 is a perspective view of the fulcrum lever.

Before proceeding with the description of the details of my construction I desire to state that the body members of my clamp 40 may be spiked to the ties before the rails are laid thereon so that the improvement thus provides a gage for the rails. The plate when clamped upon the tie may remain a permanent fixture therewith. Should 45 it be found necessary to replace a tie on which the plate rests, the securing elements between the plate and tie may be either partly or wholly withdrawn and the injured tie slipped from beneath the rails and 50 replaced by a perfect tie. The securing elements for the plate are then, of course, forced in the new tie, and thus the removal of the plate from the rail will not be necessitated.

Referring now to the drawings in detail 55 the numeral 1 designates the rails and 2 the ties on which the rails are supported.

My improved tie plate comprises a body portion or plate proper indicated by the numeral 3. The plate, adjacent one of its 60 ends is formed with an upwardly arranged inwardly flanged lug 4, disposed transversely of the plate, the said flanged lug engaging with the base flange of the rail 1. The plate 3 is centrally provided upon its 65 upper face with a substantially V-shaped depression 5 that passes through the lug 4 dividing the same, and in reality providing a lug at each side of the depression. The angular portion of the side walls provided 70 by the depression 5, adjacent to the ends of the plate may, if desired, be straight, and the plate, at its end opposite that provided with the lug 4 is formed with vertical projections 6, the side walls of which are beveled inwardly as at 7, thus providing shoulders 8 at the ends of the channel formed by the beveled portion 7 and the terminals of the side walls formed by the V-shaped portion 5. 80

The plate, upon the outer sides of the divided lug 4 is provided with alining transverse slots 9, and outward of the said slots with spike opening 10. Through these openings 10 are passed spikes 11 which enter 85 the tie 2. The plate 3, at its opposite end, and centrally between the projections 6 is provided with an additional spike opening 12.

When the body member of the plate, just 90 described, is secured on a tie, the same has received in the depression 5 thereof a wedge shaped member 13 of a thickness equaling the depth of the depression. On the outer end of the member is formed a transversely 95 arranged upstanding lipped enlargement 14, the sides of the said enlarged portion 14 being straight, but being cut longitudinally to provide horizontal walls 15 which overlie and are arranged on the straight outer surfaces of the projection 6. The said sides are then cut outwardly at an angle, as indicated by the numerals 16, and these angular edges are adapted to be received by the beveled inner walls of the projections 6. The angular portions or tongues 16 terminate in shoulders which are designed to contact with the shoulders 8 in the beveled grooves 7 to 100 105

- limit the movement of the member 13 inwardly of the plate and the lipped rail base engaging the portion 14 thereof in movement toward the rail. The enlarged end of the 5 member 13, outward of the lip 14, is brought in tight rail engaging position, to register with the opening 12, and a securing element in the nature of a spike 18 is passed through these openings and enters the tie 2.
- 10 To facilitate the longitudinal movement or adjustment of the rail engaging member 13 with respect to the plate 3, the inner and reduced end of the said member has loosely secured thereto a link 19 which is also 15 loosely connected to a fulcrum member or lever 21. The body of the member 21 is centrally slotted from its lower and widened end, a pin passing transversely through the slot to receive the outer end of the link 19.
- 20 The lever, at its lower and widened end is provided with laterally extending trunnions 22 which find a bearing in the slots 9. By swinging the lever to a vertical position, the member 13, through the medium of the link 25 connection between the said member and the lever will be swung outwardly of the plate 3 and by swinging the lever to its horizontal position, the said member 13 will be drawn inwardly over the plate to rail engaging 30 position. The lever, outward of its loose connection with the link 19 is curved as at 23, and preferably the lower wall of the depression between the spike openings 10 is provided with an angular notch 24 to receive 35 the outer end of the lever, so that the lever is thus arranged at an inclination and the lipped or clamping portion 14 of the member 13 is retained in engagement with the rail, even before the spike 18 is applied.
- 40 It is believed, from the foregoing description, when taken in connection with the drawings, the simplicity and advantages of

the construction will be apparent without further detailed description.

What I claim is:

1. A rail plate, designed to be spiked to a tie, and to receive a rail thereon, having a rail engaging flange, said plate having its upper face provided with a longitudinal depression, a member arranged in said depression and interengaged by the side walls provided by the depression, said member having a rail engaging lip, a lever fulcrumed on the plate, a link connection between the lever and said member whereby to move the 50 member to bring the lip thereon toward or away from the rail, and means for locking said member to said plate when the member is in rail engaging position.

2. A rail plate, designed to be spiked to a tie and to receive a rail thereon, having a transverse lug providing an upstanding flange to engage the rail, said plate being thickened upon its upper face at its end opposite the lug, said plate having a central 65 depression therethrough, the side walls of the depression at the thickened end of the plate being inclined inwardly, a member arranged for slidale movement in the depression having outstanding tongues at one 70 of the ends thereof received under the referred to inwardly inclined portions of the side walls of the depression, an angular lever having one of its ends provided with projecting trunnions, said plate having slots to 75 the rear of its rail engaging lug to receive the said trunnions, a link loosely connected with the member and with the lever, and spikes designed to pass through the member and through the plate and enter the tie when 80 the member is moved by the actuation of the lever to rail engaging position.

In testimony whereof I affix my signature.
WILLIAM LAFLER.
